UNITED STATES PATENT OFFICE

EDNA FLORENCE STEFFENS, OF CLEVELAND HEIGHTS, OHIO

DESIGN FOR A HUMIDIFIER

Application filed September 14, 1932. Serial No. 44,828. Term of patent 7 years.

To all whom it may concern:

Be it known that I, EDNA FLORENCE STEFFENS, a citizen of the United States, residing at Cleveland Heights, in the county of Cuyahoga and State of Ohio, have invented a new, original, and ornamental Design for a Humidifier, of which the following is a specification, reference being had to the accompanying drawing, forming part hereof, wherein—

Fig. 1 is a plan view, and Fig. 2 is a side elevation of a humidifier showing my new design.

I claim:

The ornamental design for a humidifier as shown.

EDNA FLORENCE STEFFENS.
